CLAIM

The ornamental design for a spinal plate, as shown and described.

DESCRIPTION

1. Spinal plate
- 1.1 : Perspective
- 1.2 : Front
- 1.3 : Back
- 1.4 : Left
- 1.5 : Right
- 1.6 : Top
- 1.7 : Bottom

The present design is made of metal; this design relates to a spinal plate used when performing fixation surgery on the spine in orthopedic and neurosurgery; this article is installed to support two or more lumbar vertebrae after inserting a cage, which is an artificial prosthesis, in the place of the damaged intervertebral disc between the vertebrae; the present design is a partial design; a portion for which design registration is claimed, is represented by solid lines; an unclaimed portion is represented by broken lines; a boundary between two is represented by dashed-dotted lines.
